ELECTRON DISCHARGE DEVICE

Albert E. Oberg, Elmira, N.Y., assignor to Westinghouse Electric Corporation, East Pittsburgh, Pa., a corporation of Pennsylvania

Filed June 19, 1959, Ser. No. 821,565

4 Claims. (Cl. 313—82)

This invention relates to the mounting of electrode structures in envelopes and more particularly to the mounting of an electron gun structure in an envelope of a cathode ray tube.

The conventional type electron gun now used in cathode ray tubes is usually of a unitary construction. The gun consists of a plurality of electrodes assembled and mounted together to form a structure which may be inserted as a whole into the envelope or neck of the cathode ray tube. The gun normally consists of a plurality of spaced tubular electrodes with their axes lying on the axis of the neck portion of the cathode ray tube. A plurality of insulating rods are positioned along the outer surface of the electrodes and may be parallel to the axes of the electrodes.

Pins or studs secured to the outer periphery of the electrodes are attached to the insulating rods. The studs are normally secured to the insulating rod by heating the insulating rod up to a molten state and thereafter allowing the material to cool and thereby impale the studs in the insulating rod. This provides a unitary structure of substantial strength and the electrodes are aligned and spaced during the process of sealing the stud members to the insulating rods. The electron gun is then mounted to a glass stem member. Electrically conductive lead-in members providing means of supplying the necessary potentials to the electrodes are sealed into the glass stem member. These lead-in members are welded to the electrodes and also mechanically mount the gun on the stem member. The resulting assembly is inserted into the neck of the cathode ray tube and the button like stem member is sealed to the neck. The stem member is also provided with an exhaust tubulation used in processing the tube. The front end of the gun, that is the portion projecting farthest into the neck, is usually provided with centering means which positions the electron gun within the neck. This centering means in most cases also provides an electrical contact between a coating on the interior surface of the cathode ray tube and the anode of the electron gun. The electron gun is supported in the neck by means of the lead-in members from the stem member.

It is an object of this invention to provide an improved method of supporting an electron gun within a cathode ray tube.

It is another object to provide an improved electron gun structure to provide better mounting within the cathode ray tube.

It is another object to provide means of supporting the electron gun within the cathode ray tube without disturbing the alignment of the electrode members of the electron gun.

It is another object of this invention to support the electron gun from the glass stem member without utilizing any of the electrode members.

These and other objects are effected by my invention as will be apparent from the following description taken in accordance with the accompanying drawing, throughout

which like reference characters indicate like parts, and in which:

Figure 1 illustrates a cathode ray tube embodying the teachings of my invention;

5 Figure 2 is an enlarged view of the electron gun mounted within the neck portion of the cathode ray tube of Fig. 1;

Figure 3 is a cross sectional view of Fig. 2 taken along the line III—III of Fig. 2; and

10 Figure 4 is a perspective view of the electron gun shown in Fig. 1.

Referring in detail to the drawing, the cathode ray tube consists of an envelope 12 having a neck portion 14, a flared portion 16 and a face plate portion 18.

15 An electron gun 20 is assembled and mounted to a stem member 24 and is then inserted into the neck portion 14 of the envelope 12. The stem portion may then be sealed to the neck as is shown in Fig. 2.

In the specific embodiment shown the electron gun 20 consists of a control grid 30, screen grid 32, and an anode 34 which are secured together to form a unitary structure by means of the insulating rods 40. Studs 42 are provided on the electrodes of the gun 20 and are sealed to the insulating rods 40 as previously discussed. The 20 end of the electron gun 20 which is farthest from the stem member 24 is centered in the neck portion 14 by means of a resilient spacer structure 39. A cathode electrode 31 and a heater 33 are provided in the electron gun 20 as illustrated in Fig. 3.

30 Positioned at the rear end of the electron gun 20 as shown in Figs. 2, 3 and 4 is a ring member 50 of larger diameter than the control grid member 30. A portion of the ring has been removed to facilitate radio frequency treatment of parts within the ring and clearance

35 for a high voltage lead 41. The support ring 50 is also provided with studs 52 which are sealed to the insulating members in the same process and at the same time as the assembly of the electrode members. Three stem lead members 54 are welded to spaced points about the support ring 50 and support the electron gun 20 in the neck portion 14 with respect to the stem member 24. The ring 50 operates at the same potential as the control grid 30 and therefore one of the stem leads 54 provides the necessary potential to the control grid 30 by means of a

40 flexible connector between the two members.

45 The two stem leads 56 illustrated in Figs. 3 and 4 provide means of applying the necessary potential to the heater 33 while another stem lead member 58 illustrated supplies the necessary potential to the cathode sleeve 31.

50 The stem lead 41 supplies potential to the anode 34 and a lead 60 supplies potential to the control grid 32. It can be thus seen that the support ring 50 is supported at three substantially equally spaced points about its periphery. The support ring 50 is in turn attached to the insulating rods 40 by studs 52 and provides support for the electron gun 20 from the stem member 24. The resulting support is extremely rugged. Extreme vibration of the tube resulting in distortion of the mount will not modify or change the spacing of electrodes within the gun structure. Distortion of mount structure will not modify alignment or spacing of the electrode members of the electron gun.

55 While I show my invention only in one form, it will be obvious to those skilled in the art that it is not so limited, but is susceptible to various other changes and modifications without departing from the spirit and scope thereof.

60 I claim as my invention:

65 1. A cathode ray tube comprising an envelope including a neck portion, an electron gun structure to generate an electron beam, said structure comprising in the order along said beam from a cathode, a control grid, a screen grid, and an accelerating electrode, insulating rods spaced

from said structure connected to and positioning said control grid, screen grid and said accelerating electrode with respect to each other, a centering device provided on said accelerating electrode for positioning said electron gun within said neck portion, supporting means provided in the region of said control grid comprising an annular member having projecting pins on its outer periphery which are impaled in said insulating rods and a glass stem member sealed to the end of said neck portion and provided with a plurality of stem lead members, three of said stem lead members attached to said annular member for supporting said electron gun structure within said neck portion.

2. A cathode ray tube comprising an envelope having a neck portion, an electron gun mounted within said neck portion, said electron gun comprising a unitary structure comprised of a plurality of tubular shaped electrodes, said tubular shaped electrodes being provided with projecting pins which are impaled in insulating rod members to align and position the electrodes within said unitary structure, a stem member provided at the end of said neck portion for closing off said neck portion and supporting said electron gun within said neck portion, a support ring positioned at the end of said electron gun adjacent said stem member and of a larger diameter than the adjacent electrode member, said support ring also provided with projecting pins which are impaled in the insulating rod members and stem lead members provided in said stem member and secured to said support ring to support said unitary gun structure within said envelope.

3. A cathode ray tube comprising an envelope having a neck portion, an electron gun positioned within said neck portion, said electron gun comprising a plurality of electrodes spaced along the axis of said neck portion, said electrodes provided with a plurality of projecting pins which are impaled in insulating rod members positioned along said electron gun structure to align and position the electrode members of said electron gun in a unitary structure, support means provided at the end of said neck portion for mounting said electron gun within said tube neck, said support means comprising a stem mem-

ber through which lead-ins are provided for applying voltages to said electrode members, said stem member provided with at least three stem support members projecting into the interior portion of said neck portion, an annular support ring positioned at the end of said electron gun adjacent said stem member, said support ring of a larger diameter than said electrode members, said support ring provided with projecting pins which are impaled in said insulating rod members and having said stem support members secured to said ring to support the electron gun structure within said neck portion.

4. A cathode ray tube comprising a face plate, a flared portion and a neck portion, an electron gun provided within said neck portion for generating an electron beam to scan said face plate portion, said electron gun comprising a plurality of electrodes positioned substantially along the axis of said neck portion, the electrodes of said electron gun structure secured together to provide a unitary structure, said electrodes having a plurality of pins provided about their outer periphery which are impaled in a plurality of insulating rod members, said rod members substantially parallel to the axis of said neck portion, centering means provided at the end of the electron gun nearest said face plate for centering said electron gun within said tubular neck, support means provided at the opposite end of said gun for mounting said electron gun within said tubular neck, said support means comprising an annular ring coaxial with the electrode of said gun farthest from said face plate, said ring having pins thereon impaled in said insulating rods, a stem member provided in said neck portion for closing off the end of said neck portion and having a plurality of stem lead members which are secured to said ring to support the electron gun within the neck portion of said tube.
